UNITED STATES PATENT OFFICE.

CARROLL MELVINE BELL, OF GREENCASTLE, INDIANA, ASSIGNOR TO HIMSELF, WILLIAM ELIJAH ARNOLD, GEORGE EDWARD BLAKE, AND HENRY SILAS RENICK, OF SAME PLACE.

MOTOR.

SPECIFICATION forming part of Letters Patent No. 617,222, dated January 3, 1899.

Application filed November 24, 1897. Serial No. 659,668. (No model.)

To all whom it may concern:

Be it known that I, CARROLL MELVINE BELL, of Greencastle, in the county of Putnam and State of Indiana, have invented a new and Improved Motor, of which the following is a full, clear, and exact description.

The object of the invention is to provide a new and improved motor which is simple and durable in construction, very effective in operation, and arranged to utilize the motive agent to the fullest advantage, the motor being capable of driving various machinery, to act as an air or water pump, &c.

The invention consists of novel features and parts and combinations of the same, as will be fully described hereinafter and pointed out in the claims.

Reference is to be had to the accompanying drawings, forming a part of this specification, in which similar characters of reference indicate corresponding parts in all the figures.

Figure 1 is a sectional side elevation of the improvement. Fig. 2 is a plan view of the same with parts in section. Fig. 3 is an enlarged sectional plan view of part of the improvement on the line 3 3 of Fig. 1; and Fig. 4 is a sectional plan view of the shoe and track, the section being taken on the line 4 4 of Fig. 1.

30 The improved motor is provided with two horizontally-disposed wheels A and B, having hollow shafts A' and B', respectively, journaled in suitable bearings in a frame C of any approved construction. The wheels A and B are provided with two sets of gear-wheel rims A² A³ and B² B³, respectively, of which the rim A² meshes with the rim B² and the rim A³ meshes with the rim B³, so that when one wheel is rotated the other wheel rotates 40 with it.

On the upper end of the hollow shaft A' is secured a pulley D, connected by a belt D' with a pulley D² on an engine E or other motor of any approved construction, the engine, 45 as shown, being driven by compressed air or gas contained in a reservoir F, connected with the cylinder of the engine. Thus when the engine E is in motion a rotary motion is given to the shaft A' by the belt D' and pulleys D²

D, so that the wheel A is rotated and its rotary motion is transmitted to the other wheel B, as previously mentioned.

The motor illustrated in the drawings is arranged for pumping water or other liquid, and for this purpose the upper rims A³ and B³ of the wheels A and B carry a number of duplex pumps G, preferably four in number for each wheel and arranged equidistant apart, as is plainly indicated in Fig. 2, and having suction-pipes G' for the pump-cylinders, said pipes being connected with the hollow shafts A' and B' below partitions A⁴ and B⁴, respectively, and the discharge-pipes G² of the several pumps being connected with the hollow shafts A' and B' above said partitions, as is plainly indicated in Fig. 1. The lower ends of the hollow shafts A' and B' are connected by pipes H with the water or other liquid to be elevated, and the upper ends of the said shafts are connected by pipes H' with a pipe 70 H² for carrying the discharged or pumped water or other liquids to any desired place.

The piston-rods G³ G⁴ for each duplex pump G are connected with each other in such a manner that when one piston-rod moves inward the other moves outward, or vice versa. For this purpose the outer ends of the piston-rods G³ G⁴ are provided with pivoted extension-arms G⁵ G⁶, pivotally connected with levers I I', respectively, fulcrumed on the rims A³ B³ of the wheels A and B. The levers I and I' are pivotally connected by links I² I³ with a lever I⁴, fulcrumed at its middle on the said rims, so that the motion given to one piston-rod imparts motion to the other piston-rod in a reverse direction.

The outer ends of the extension-arms G⁵ G⁶ are alternately acted upon by weighted arms J, carried alternately on the peripheries of the wheels A and B, the said weighted arms 90 being mounted to swing, and they are caused to swing by centrifugal force for working the piston-rods of the pumps and actuating the latter to pump water or other liquid in the usual manner. As illustrated in the drawings, eight such weighted arms J are provided, one for each duplex pump, it being understood that each of the said arms travels in an

8-curve along the lines of the peripheries of the wheels A and B. Now in order to accomplish this movement of the weighted arms I provide the following device: Each weighted arm J is pivoted in the upper end of a frame K, disposed vertically and adapted to be carried around the peripheral surfaces of the wheels A and B, as hereinafter more fully described. Each weighted arm J is provided 5 at its upper end with oppositely-arranged sets of wings forming pushing-heads J' J², of which the head J' serves to move in contact with the arms G⁵ G⁶ for the duplex pumps G on the wheel A, and the pushing-head J² is adapted 10 to move in contact with the arms G⁵ and G⁶ 15 of the duplex pumps located on the wheel B.

Each frame K is formed near its lower end with a horizontally-disposed boss K', formed in its ends with recesses K² K³ for engagement 20 with teeth A⁵ B⁵, respectively, held in the peripheral surfaces of the rims A² B², respectively. The rims A² and B² are of the same diameter, and the teeth A⁵ B⁵ are arranged in 25 pairs in such a manner that they come opposite each other at the meeting-point of the wheels, as will be readily understood by reference to Fig. 3, the teeth being, however, sufficiently set inward on the rims so as not to touch each other, but to move in mesh with 30 the recesses K² and K³, respectively.

On the boss K' for each frame K is fulcrumed a catch L, made in the form of a three-armed lever, of which the downwardly-extending arm L' is provided with a shoe L², 35 fulcrumed on the said arm and adapted to travel in an 8-shaped groove N, formed in the frame C and having the main portions concentric to the wheels A and B and the meeting ends crossing each other, as is plainly indicated in Fig. 4. The ends of the horizontal arm of the catch L are formed into hooks L³ L⁴, adapted to alternately engage hooks O O', secured to the rims A² B² of the wheels A and B, respectively. The horizontal arm of 40 the catch L is also provided with links L⁵ L⁶, fitted to slide at their upper ends in bearings K⁴, formed on the frame K, the said bolts being adapted to alternately engage keepers O² O³, attached to the under side of the rims A³ 45 and B³, respectively, of the wheels A and B. Thus when the shoe L² travels in that portion 50 of the groove N under the wheel A, as shown at the right in Fig. 1, then the catch L is engaged by its hook L³ with the corresponding hook O, and the link L⁵ is in engagement with the keeper O², so that the frame K is firmly 55 secured or held in position on the peripheral surface of the wheel A.

When the wheel A is rotated, the weighted 60 arm J, owing to centrifugal force, swings with its weight outward and with its pushing-heads inward to cause the pushing-head J' to act on the corresponding arm G⁶ of the piston-rod G⁴, so as to push the piston therein inward 65 in the cylinder of the corresponding duplex pump G during the revolution of the wheel A. Now when the frame K, after having

made a revolution, comes to the meshing-points between the two wheels A and B then the shoe L² travels over into that part of the groove N concentric to the other wheel B, and said shoe L² in traveling over the crossing imparts a swinging motion to the three-armed lever forming the catch L to move the hook L³ outward in engagement with the hook O 70 and to unlock the link L⁵ from the keeper O². At the same time the other hook L⁴ is moved into mesh with the hook O' and the link L⁶ is moved in engagement with the keeper O³ on the wheel B. Thus the frame K is released 75 from the wheel A and is rigidly connected with the peripheral surface of the wheel B. Now as the latter rotates the weighted arm J swings outward at its lower end by centrifugal force—that is, in an opposite direction 80 to that it had while moving with the wheel A—and in doing so the upper end of the said weighted arm J swings inward and the pushing-head J² engages the arm G⁵ of the piston-rod G³ for the corresponding duplex pump G 85 on the wheel B. Thus the duplex pump G is actuated during the revolution of the wheel B. When the frame K comes again to the meeting-point of the two wheels, it is transferred to the other wheel A by the shoe 90 L² traveling across the intersection of the grooves from the wheel B to the wheel A. It is understood that when this movement takes place another swinging motion is given to the catch L by the shoe L² during the passage of 95 the said shoe through the intersection of the groove to release the hook L⁴ from the catch O' and to release the bolt L⁶ from the keeper O³ and at the same time move the other hook L³ in engagement with the hook O and the 100 bolt L⁵ in engagement with the keeper O² on the wheel A. The above-described operation is then repeated—that is, the weighted arm J while traveling on the wheel A causes its pushing-head J' to actuate the duplex 105 pump G.

Now by reference to Figs. 2 and 3 it will be seen that two teeth A⁵ and B⁵ are used for each duplex pump G as the same arm J is used on the wheel A for operating one piston-rod of 110 a single cylinder of a duplex pump and for operating the other piston-rod of the single cylinder for the duplex pump on the wheel B.

The upper end of each frame K is preferably formed in the shape of a cylindrical boss 115 K⁵, in which the corresponding arm J is pivoted, and which boss at the time the said frame passes through the meshing part of said rims passes into semicircular recesses cut in the rims A³ B³. 120

Now it is evident that when the engine E is in motion and a rotary motion is given to the wheels A and B in the manner described then the several frames K follow one upon the other around the peripheral surfaces of 130 the wheels A and B—that is, in the path of an 8-curve—so that the arms J receive an alternate swinging motion for actuating the duplex pumps G on the two wheels A and B. 125

Thus water is drawn in through the suction-pipes H, the hollow shafts A' B', and the suction-pipe G', and water is discharged from the pumps G through the pipes G², the upper 5 ends of the hollow shafts A' B', the pipes H', and the common pipe H², leading the water to a suitable place of discharge.

Having thus fully described my invention, I claim as new and desire to secure by Letters 10 Patent—

1. A motor provided with a driving-gear consisting of wheels in mesh with each other, pumps carried by the said wheels, weights actuated by the centrifugal power of the driving-gear and operating said pumps and means for transferring the said weights from one of the said wheels to the other, substantially as described.

2. A motor comprising wheels mounted to 20 turn and in mesh with each other, weighted arms carried on the peripheries of the wheels and mechanism for giving the weighted arms a movement in opposite directions the said weighted arms being adapted to operate machinery carried by the said wheels, substantially as set forth.

3. A motor comprising an engine, a driving-gear consisting of wheels in mesh with each other, and frames arranged to travel around 30 the peripheral surfaces of the said wheels in the path of an 8-curve, each frame having a weighted arm, and pumps arranged on the said wheels, and adapted to be actuated by the said weighted arms, substantially as shown and described.

4. A motor comprising wheels mounted to turn and in mesh with each other, frames traveling on the peripheral surfaces of the said wheels in the path of an 8-curve, weighted 40 arms on the said frames, and pumps carried by the said wheels, and adapted to be actuated by the said weighted arms, substantially as shown and described.

5. A motor comprising wheels in mesh with 45 each other, means for driving one of the wheels, a frame adapted to travel on the peripheral surfaces of the said wheels in the path of an 8-curve, means, substantially as described, for transferring the said frame 50 from one wheel to the other while in motion, at the intersection of the wheels, and a weighted arm pivoted on each of the frames, and adapted to actuate machinery carried by the wheels, as set forth.

55 6. A motor comprising a fixed main frame provided with a path in the form of an 8,

wheels journaled in the said frame concentric to the main portions of the said path, the wheels being in mesh with each other, a frame adapted to be carried at the peripheral surfaces of the said wheels, a weighted arm pivoted on each of the said frames, and adapted to actuate machinery, and means for alternately locking the said frame to the said wheels, the said means comprising a catch in the form of a three-armed lever, a shoe on one of the arms of the lever, and engaging the said 8-path, catches on the said wheels for engagement with hooks on the catch, bolts carried by the said catch, and keepers on the 70 said wheels, and adapted to be engaged by the said bolts, substantially as shown and described.

7. A motor comprising wheels having hollow shafts and mounted to turn, the said 75 wheels being in mesh with each other, frames carried by the said wheels and adapted to be transferred from one wheel to the other, weighted arms on the said frames, the said weighted arms when on one wheel having 80 movement in a direction opposite to that which they have when on the other wheel and pumps carried by the said wheels and adapted to be actuated by the said weighted arms, the said pumps being connected with the said 85 hollow shafts, substantially as shown and described.

8. A motor comprising wheels mounted to turn and provided with hollow shafts each having a transverse partition, the said wheels 90 being in mesh with each other, duplex pumps carried by said wheels and having their suction and discharge pipes respectively connected with the said hollow shafts at opposite sides of the partitions, the said hollow shafts 95 being connected at one end by pipes with the liquid to be elevated and at the other end with pipes leading to a discharge, weighted arms operated by the centrifugal power of the said wheels and actuating the said pumps, 100 mechanism for giving the weighted arms a movement in both directions, and means for connecting the piston-rods of each duplex pump, whereby the motion given to one piston-rod will impart motion to the other piston-rod 105 in a reverse direction substantially as shown and described.
